UNITED STATES PATENT OFFICE.

GEORGE H. GILMAN, OF CLAREMONT, NEW HAMPSHIRE, ASSIGNEE TO SULLIVAN MACHINERY COMPANY, OF BOSTON, MASSACHUSETTS, A CORPORATION OF MASSACHUSETTS.

FEED-CONTROLLING DEVICE.

1,151,261.

Specification of Letters Patent. Patented Aug. 24, 1915.

Application filed December 26, 1914. Serial No. 879,026.

To all whom it may concern:

Be it known that I, GEORGE H. GILMAN, a citizen of the United States, and a resident of Claremont, Sullivan county, New Hampshire, have invented an Improvement in Feed-Controlling Devices, of which the following description, in connection with the accompanying drawings, is a specification, like characters on the drawings representing like parts.

This invention relates to feed controlling devices for tools, and more especially, though not exclusively, to means for controlling the action of the pressure fluid feed cylinder, and piston of a pressure fluid impact tool, such for example as a stoping rock drill.

My invention will be best understood by reference to the following description, when taken in connection with the accompanying drawings of two illustrative embodiments thereof, while its scope will be more particularly pointed out in the appended claims.

In the drawings, Figure 1 is a central, longitudinal sectional view, partly in elevation, of one form of stoping drill having a feed-controlling device embodying my invention; Fig. 2 is a central, longitudinal sectional view, partly in elevation, of another form of stoping drill having a feed-controlling device embodying my invention; Fig. 3 is a sectional view, on an enlarged scale, on line 3—3 of Fig. 2, looking toward the left; and Fig. 4 is a sectional view, on an enlarged scale, on line 4—4 of Fig. 2, looking toward the right.

Referring to the drawings, and to both embodiments of my invention which I have selected for illustration, I have there shown two examples of stoping drills, each comprising work-performing means including a cylinder 5, having therein a piston 6, provided with a reduced extension or hammer bar 7, adapted to deliver a succession of blows upon a suitable impact-receiving member, herein in the form of a striking pin 8, the latter in turn acting upon the inner end of an appropriate drill-bit 9 in a familiar manner, to cause the drill by its percussive action to drill a hole in the rock. The cylinder 5 is provided with a rear cylinder head 10, which may be of any other appropriate construction, but herein constitutes a mounting for a throttle valve 11 for controlling the admission of the pressure fluid to the tool.

As a means for advancing the impact motor, thereby to press the drill-bit against its work, the tool may be provided with any appropriate feeding means, as for example a pressure fluid feeding means comprising a feed piston and cylinder secured, the one part to the rear cylinder head, and the other arranged to engage a suitable abutment, as for example the floor or side wall of the tunnel or other space in the mine or quarry where the tool is being operated.

In the form shown in Fig. 1, the feeding means comprises a feed cylinder 12, secured to the cylinder head 10, and having at its rear end a cylinder head 13, through which passes a piston rod 14, the latter being secured to a feed piston 15 working in the feed cylinder. In this example, the feed piston rod 14 is provided with a spur 16, for engagement with the wall or floor of the mine.

In the form shown in Fig. 2, the feeding means comprises a feed cylinder 17, having a front cylinder head 18, through which passes a piston rod 19, the latter being secured at one end to the cylinder head 10, and at its other end to a feed piston 20 working in the feed cylinder 17. In this form, the piston rod and feed piston are provided with an axial passage 21, through which the pressure fluid passes to the rear end of the cylinder, where it may act upon the rear end of the feed piston. In this instance, the feed cylinder 17 is provided with a spur 22 for engagement with the wall or floor of the mine or quarry.

Both forms of stoping drills, as thus far described, are of well known construction, and require no further description. I will now describe the feed controlling means, whereby the feed may be regulated, or altogether stopped at will.

In a great many cases, the rock which is encountered is comparatively soft, and does not require the full pressure of the feeding device to keep the drill up to its work. In many cases, also, soft and seamy spots in the rock are encountered, and when this is the case, there is a tendency of the drill to jump forward suddenly under the influence of its feeding device, thus causing the drill-bit to become jammed.

As a means for controlling the feed, and to provide for the manual regulation of the same, I have herein provided a frictional

restraining device, which is similar in its construction as applied to both forms of stoping drill illustrated, and a detailed description of that which is more fully illustrated in Figs. 2, 3 and 4, will suffice for both.

Referring to Figs. 2, 3 and 4, the restraining device selected for illustration comprises an elastic helically-coiled member 23, encircling the piston rod 19 and adapted to engage the latter with a greater or lesser degree of pressure, whereby its feed restraining capacity may be varied. To this end, the coiled spring-like member is herein 10 closed in a casing 24 attached to the cylinder head 18 in any appropriate manner, as by threading the two together. Within this casing is journaled a sleeve 25, to which one 15 end of the helically-coiled member 23 may be secured in some appropriate manner, as by providing the sleeve with a longitudinal slot 26 to receive the terminal portion of the spring, which is bent radially to form a lug 27. As a means for holding the opposite 20 end of the helically-coiled member fixed, it is herein bent radially to form a lug 28, which enters a slot 29 provided in the casing 24.

It will now be apparent that by rotating 30 the sleeve 25, the helically-coiled member 23 may be flexed and caused to expand or contract at will, according to the direction in which the sleeve is rotated. In other words, the diameter of the coil or coils may be enlarged or reduced by subjecting it to a torsional stress in the proper direction, thus 35 varying the degree of pressure which it will exert upon the piston rod 19, owing to the fact that it is wrapped about the latter in frictional contact therewith. It will be 40 readily appreciated that by this means, the desired frictional resistance may be obtained, and may be regulated at will, without causing a side thrust to be exerted against the 45 piston rod. This, of course, is due to the fact that the coils engage the piston rod with substantially equal pressure throughout its circumference.

The sleeve 25 may be rotated and held 50 fixed in the desired position of adjustment by any suitable means, and as herein shown, the sleeve is in the form of a worm gear, meshing with a worm 30. The latter is 55 herein suitably formed on a worm-shaft 31, whose inner end is journaled in the casing 24, and whose outer end is journaled in a bushing 32 and is provided beyond the latter with a suitable handle 33. The workman, by grasping the handle 33, may turn 60 the worm 30, thereby turning the worm-gear ring or sleeve 25, and hence winding or unwinding the spring-like coiled member 23, and causing the latter to engage the piston rod with a greater or less degree of effectiveness.

By providing a worm and worm gear of the proper pitch as shown, the adjusting device is rendered automatically locking,—that is to say, it is securely locked in the desired position of adjustment, without further 70 thought, upon the completion of the adjusting operation.

Referring to the form shown in Fig. 1, the construction is the same in all essential particulars as that already described, except 75 that it is attached to the rear cylinder head of the feed cylinder.

In the operation of either form of the invention, the full effect of the feeding means may be obtained by turning the regulating 80 handle to a position which will cause the helically-coiled member to become entirely relaxed. If, however, the character of the rock should be such as to require a less degree of pressure, the action of the feeding device may be regulated to a nicety by simply turning the regulating handle to the proper extent. If, during the operation of 85 the drill, the drill-bit should strike a soft spot and tend to jump forward suddenly, the restraining device imposes such a restraint thereon as to prevent the drill-bit from becoming wedged, or jammed.

While I have herein shown and described 90 two specific embodiments of my invention for illustrative purposes, and have disclosed and discussed in detail the construction and arrangement incidental to two specific applications thereof, it is to be understood that 95 the invention is limited neither to the mere details or relative arrangement of parts, nor to its specific embodiments herein shown, but that extensive deviations from the illustrated forms or embodiments of the invention 100 may be made, without departing from the principles thereof.

Having thus described my invention, what I claim and desire by Letters Patent to secure is:—

1. The combination with work-performing means and means for feeding said work-performing means; of feed-controlling means including an elastic feed-restraining member and means for flexing said member to vary its feed-restraining capacity.

2. The combination with work-performing means and means for feeding said work-performing means; of feed-controlling means including an expandible and contractible feed-restraining member, and means for expanding and contracting said member to vary its feed-restraining capacity.

3. The combination with work-performing means and means for feeding said work-performing means; of feed-controlling means including a coiled feed-restraining member, and means for enlarging and reducing the coil or coils of said member to vary its feed-restraining capacity.

4. The combination with work-perform-

ing means and means for feeding said work-performing means; of feed-controlling means including a helical feed-restraining member, and means for subjecting said member to a torsional stress to change its feed-restraining capacity.

5. The combination with feeding means comprising two telescopically arranged members; of means for regulating their telescopic movement including an elastic member engaging one of said telescopically arranged members, and means for flexing said elastic member to cause it to engage with a greater or less degree of effectiveness.

10. 6. The combination with feeding means comprising two telescopically arranged members; of means for regulating their telescopic movement including an elastic member encircling one of said telescopically arranged members, and means for varying the diameter of said elastic member to vary its feed-regulating effect.

15. 7. The combination with feeding means comprising two telescopically arranged members; of means for regulating their telescopic movement including an expandible and contractible feed-restraining member encircling one of said telescopically arranged members, and means for expanding and contracting said feed-restraining member to vary its feed-restraining capacity.

20. 8. The combination with feeding means comprising two telescopically arranged members; of means for regulating their telescopic movement including a coiled feed-restraining member encircling one of said telescopically arranged members, and means for enlarging or reducing the coil or coils of said feed-restraining member to vary the feed-restraining capacity.

25. 9. The combination with feeding means comprising two telescopically arranged members; of means for regulating their telescopic movement including a helical feed-restraining member encircling one of said telescopically arranged members, and means for subjecting said feed-restraining member to a torsional stress to change its feed-restraining capacity.

30. 10. The combination with two telescopically arranged members; of means for regulating their telescopic movement including a helical member coiled about one of said telescopically arranged members and having one portion held fixed as to circumferential movement, and means connected to another portion of said helical member to subject the same to a torsional stress.

35. 11. The combination with two telescopically arranged members; of means for regulating their telescopic movement including a helical member coiled about one of said telescopically arranged members and having one portion held fixed as to circumferential movement, and means including a ring co-

axially disposed with relation to said helical member to subject the same to a torsional stress.

40. 12. The combination with two telescopically arranged members; of means for regulating their telescopic movement including a helical member coiled about one of said telescopically arranged members and having one portion held fixed as to circumferential movement, and means including a toothed ring coaxially disposed with relation to said helical member to subject the same to a torsional stress.

45. 13. The combination with two telescopically arranged members; of means for regulating their telescopic movement including a helical member coiled about one of said telescopically arranged members and having one portion held fixed as to circumferential movement, and means connected to another portion of said helical member to subject the same to torsional stress and to hold the same fixed in the desired condition of stress.

50. 14. The combination with two telescopically arranged members; of means for regulating their telescopic movement including a helical member coiled about one of said telescopically arranged members and having one portion held fixed as to circumferential movement, and means including a toothed ring coaxially disposed with relation to said helical member and a device engaging the teeth of said ring to subject said helical member to a torsional stress and to hold the same fixed in the desired condition of stress.

55. 15. The combination with two telescopically arranged members; of means for regulating their telescopic movement including a helical member coiled about one of said telescopically arranged members and having one portion held fixed as to circumferential movement, and means including gearing to subject said helical member to torsional stress.

60. 16. The combination with two telescopically arranged members; of means for regulating their telescopic movement including a helical member coiled about one of said telescopically arranged members and having one portion held fixed as to circumferential movement, a gear secured to another portion of said helical member and coaxially disposed with relation thereto, and another gear meshing with the first-mentioned gear to turn the latter.

65. 17. The combination with two telescopically arranged members; of means for regulating their telescopic movement including a helical member coiled about one of said telescopically arranged members and having one portion held fixed as to circumferential movement, a worm gear secured to another portion of said helical member and coaxially disposed with relation thereto, and a worm meshing with said worm gear.

18. The combination with two telescopically arranged members; of means for regulating their telescopic movement including a helical member coiled about one of said telescopically arranged members and having one portion held fixed as to circumferential movement, a worm gear secured to another portion of said helical member and coaxially disposed with relation thereto, a worm meshing with said worm-gear, and a casing inclosing said helical member, said worm gear and said worm.
19. The combination with two telescopically arranged members; of a helical member coiled about one of said telescopically arranged members, a worm gear coaxially disposed with relation to said helical member.

ber, a worm meshing with said worm-gear, and a casing inclosing said helical member, said worm-gear and said worm, said casing 20 and said worm gear being each provided with a slot extending lengthwise of the axis of said helical member, and the latter being provided adjacent its opposite ends with projections extending into said slots, respectively. 25

In testimony whereof, I have signed my name to this specification, in the presence of two subscribing witnesses.

GEORGE H. GILMAN.
